UNITED STATES PATENT OFFICE.

EARL W. MASON AND CHESTER D. MILLER, OF LOS ANGELES, CALIFORNIA.

ROAD-MAP.

1,395,509.

Specification of Letters Patent.

Patented Nov. 1, 1921.

Application filed March 31, 1920. Serial No. 370,155.

To all whom it may concern:

Be it known that we, EARL W. MASON and CHESTER D. MILLER, citizens of the United States, both residing at Los Angeles, in the 5 county of Los Angeles, State of California, have invented new and useful Improvements in Road-Maps, of which the following is a specification.

This invention relates to road maps and it 10 is an object of the invention to provide a simple, effective, and extremely inexpensive device of that character.

The present invention relates generally to road maps of the character set forth in our 15 co-pending application entitled "Road maps" Serial No. 317,084, filed August 12, 1919, and it has for an object the provision of an improved simplified device of that general character. Further, it will be understood 20 that the invention is not limited to road maps to be used by motorists but that it may be employed to carry maps for aviators, etc.

A particular and noteworthy feature of 25 the device provided by the invention is its simple, compact construction and arrangement. The extreme simplicity of construction renders the device easily and therefore inexpensively manufactured while its compactness makes it convenient and sightly.

A further feature of the invention is the manner in which the map carrying spools are 30 removably mounted in the casing. Each spool is mounted on a rod which is not detachable from the casing but may be released at one end from the casing and moved to a position where the spool may be removed from it.

Other objects and features of the invention 35 are set forth in, and will be understood from, the following specification of a preferred embodiment of the invention throughout which reference is had to the accompanying drawings in which—

40 Figure 1 is a face view of the device; Fig. 2 is a detail sectional view taken as indicated by line 2—2 on Fig. 1; Fig. 3 is a detail sectional view taken as indicated by line 3—3 on Fig. 2; Fig. 4 is a detail sectional view taken as indicated by line 4—4 on Fig. 1; Fig. 5 is a plan view taken as indicated by line 5—5 on Fig. 2; Fig. 6 is an enlarged detail sectional view of one end portion of one of the spool carrying rods showing the 45 manner in which the spool is held against

rotation relative to the rod and also the spring which opposes rotation of the rod and spool; Fig. 7 is a view showing the casing opened with a part of the body of the casing broken away, to show the manner in which the spools may be placed in or removed from the casing; and Fig. 8 is a sectional view of the casing showing the manner in which the guide rollers are mounted.

Throughout the drawings the numeral 10 designates the map which is mounted on and extends between two spools 11. The spools 11 are removably carried on pins or rods 12 rotatably carried in a suitable casing 13.

The map 10 is a comparatively long narrow strip of paper or other like flexible, more or less transparent, material and has printed or otherwise suitably marked on it information and data desirable and valuable to motorists. In the preferred form of map 70 the paper or strip of flexible material is black on its outer face and the marks are white. The map is removable from the spools 11 so that various suitable maps may be arranged in the casing at the motorist's 75 convenience. The ends of the map 10 are somewhat tapered and are arranged through slots 14 in the spools 11. The slots 14 are comparatively long and narrow and are arranged diametrically through the spools to 80 intersect the bores 15 which carry the rods 12. In practice, the ends of the map 10 are placed through the slots 14 in the spools before the spools are arranged on the rods 12 so that when the spools are placed on the 85 rods the portions of the map at the bores 15 are pushed to one side and firmly held or clamped between the sides of the bores 15 by the rods, as shown in Figs. 3 and 4.

The casing 13 comprises a flat rectangular 90 base 17 adapted to be mounted on or secured to the dash or other suitable part of the vehicle. The base 17 is preferably formed of sheet metal and has outwardly extending flanges 17^a at its edges. The body of the 95 casing, which is adapted to fit over and be carried by the base 17, comprises side walls 18 and 19, and walls 20 and 21, and a transparent top plate 22. The end wall 21 of the body is hinged at 23 to the base 17 and the 100 end wall 20 of the body carries a spring catch 24 which coöperates with an inwardly bent portion 25 of the flange 17^a at the upper end of the base, to hold the body to the base, as clearly shown in Figs. 1, 2, 3, 4, and 8 of the 105 110

drawings. The spring catch 24 is preferably secured to the end wall 20 by a rivet 26 having a head 27 at the outside of the casing which forms a knob or handle by 5 which the body of the casing may be operated or gripped in order to open or close it. The top plate 22, which is preferably glass, is secured to the inwardly turned edges of the side walls and end walls by a suitable metal 10 beading 28, as clearly shown in Figs. 1, 2, 4, 7 and 8 of the drawings.

The rods 12 which carry the spools 11 are mounted at the ends of the casing 13 being carried in suitable bores 30 in the side wall 15 19 so as to extend across or through the casing and into bores 31 in the side wall 18. The rods 12 project somewhat from the wall 19 and carry knobs 32 by which they 20 may be turned or rotated. Suitable helical springs 33 are carried on the rods 12 between washers 34 and the inner faces of side wall 19, as clearly shown in the drawings. The washers 34 are held in place on the rods 12 by suitable U-shaped wire keys 25 35 which extend through bores 36 in the rods 12. The springs 33 being interposed between the washers 34 and side wall 19 tend at all times to hold the knobs 32 in engagement with or against the side wall 19 and also tend 30 to keep the rods 12 in place in the bores 31 in side wall 18. When the spools 11 are arranged on the rods 12 the keys 35 engage or extend into slots 38 in the ends of the spools, and the flange members 39^a, which are 35 arranged at the ends of the spools, engage the washer 34, as clearly shown throughout the drawings. The engagement of the slots 38 by the keys 35 lock the spools and rods together against relative rotary movement so 40 that rotation of the knobs 32 will cause rotation of the spools 11. It will be noted in the drawings, particularly in Fig. 3 of the drawings, that the bores 31 are in indentations 39 formed in the side wall 18. The indentations 39 are engaged by the ends of the spools 11 and cause the spools to be properly spaced from the side wall 18 so that the map 10 will 45 properly register with the top plate 22. When the spools are in place in the casing 50 they are frictionally held against rotation by the springs 33. The springs 33 cause the washers to bear against the spools thereby causing the spools to bear against the indentations 39. Further it will be noted 55 that the rods fit comparatively loosely through the bores 30 and that they are only sufficiently long to extend completely through bores 31.

When it is desired to place spools on or 60 remove them from the rods 12 the casing 13 may be opened, by swinging the body of the casing away from the base 17, as shown in Fig. 7, and the knobs 32 on the rods 12 may be moved or drawn away from the side wall 65 19, compressing the springs 33, until the ends

of the rods 12 have been withdrawn from the bores 31. The rods 12 may then be positioned, as shown in Fig. 7, allowing the spools to be easily and conveniently placed on or removed from them.

70

Before the spools 11 are placed in the casing 13 the map 10, which is to be arranged to extend between them, is arranged over guide rollers 41 carried between the side walls 18 and 19 near the ends of the top plate 22, as 75 clearly shown in Figs. 2, 4, 7 and 8. The guide rollers 41 are formed with trunnions 41^a, at their ends, which are carried in bores 41^b in the side walls 18 and 19. The guide rollers 41 guide the map 10 so as to keep 80 it properly arranged or stretched under the top plate 22.

80

An electric light or bulb 40 is carried in a clamp or socket 42 in the casing 13 so as to be below the portion of the map 10 which is between the guide rollers 41. The bulb 40 is provided so that the map 10 can be effectively illuminated, or made visible, at night or in the dark. The socket 42 comprises two spring arms 42^a and is mounted 90 on a suitable bracket 43 secured to the base 17 by rivets 44 or other suitable means. The arms of the socket are provided with suitable notches 45 to receive the pins 46 which project or extend from the base 47 of the bulb 40. The arrangement of the pins 46 in the notches 45 prevents longitudinal displacement, or movement, of the base 47 in the socket 42. One side of the circuit, adapted to supply the bulb 40, is grounded either 100 on the casing 13 or on the structure on which the casing is mounted while the other side of circuit connects to a movable contact 50 adapted to be moved into engagement with or away from the contact 51 arranged at the 105 end of base 47. The contact 50 comprises a bolt carried on, and insulated from, a spring arm 52 secured to the base 17 at 53. A lead wire 54 extends into the casing 13 through a bore 55, in the base 17, and connects to the bolt or contact 50 in the manner shown in Figs. 2, 3, and 7. The spring arm 52 is arranged to normally hold the contact 50 out of engagement with the contact 51, as shown in Fig. 3, and is adapted to be 110 moved inwardly so as to cause the contact 50 to engage contact 51 in the manner shown in Fig. 5. In order to provide a means for operating or moving the spring arm 52 and for holding it in the position shown in Fig. 5 an extension 60 is formed on the arm 52 to extend through a slot 61 in the flange 17^a formed at the edge of base 17. The extension 60 projects from the casing 13 forming a convenient grip for the operator. A 115 120 suitable notch 63 is formed in the extension 60 to engage a side of the slot and hold the spring arm 52 in the position shown in Fig. 5 when it is desired to leave the bulb 40 burning. When the notch 63 is in en- 130 125 130

gagement with the side of the slot 61 and it is desired to release the arm 52 and turn off the bulb 40, it is merely necessary to move the extension 60 in the direction indicated 5 by the arrow in Fig. 5 and then allow it to be moved outwardly from the casing by the resiliency of arm 52. This particular control mechanism is very simple and inexpensive in construction and is extremely con- 10 venient and effective.

It will be noted that the bracket 43 is shaped and arranged in the casing to form a carrier or pocket for a book 81. The book 81, to be carried in the carrier formed by the 15 bracket 43, may be of any desired character; for instance it may be a note book or a book of general information to be used in connection with, or for explanation of, the map 10. To permit of convenient placing of the 20 book in or removal of the book from the carrier the flange at one side of the base 17 is turned down at 80 as clearly shown in Figs. 2, 3 and 7.

The hinged connection 23 between the 25 body of the casing and the base of the casing comprises a rod or pin 23^a. The pin 23^a is removable from the body and base to allow the body to be detached from the base. In practice the body and base being hinged 30 together makes it easy and convenient for the motorist to open the casing to obtain the book 81, while the body being detachable from the base allows the motorist to completely remove the body in order to easily 35 and conveniently place a map in or remove a map from the device. When it is desired to carry several maps showing different parts of the country, etc., the extra maps, or the maps in addition to the one carried 40 on the spools 11, may be carried in clips 90 which are mounted on the bracket 43. The clips 90 are preferably simple spring clips arranged to carry the maps in the manner shown in Figs. 2 and 3 of the drawings.

45 Having described a preferred form of our invention, we claim:

1. In a device of the character described, a casing comprising a base and a body hinged to the base, the body comprising ends, sides 50 each formed with bores and one formed with indentations at the bores, and a sight opening, two rods carried in said bores to extend through the casing, and so that each rod has only one of its ends removable from the bore 55 which carries it, two spools, one removably carried on each rod to have one end in engagement with an indentation, means for preventing relative rotary movement between the spools and the rods, means for 60 yieldingly holding the spools against the indentations, said means comprising resilient members mounted in the rods and contacting with the inner wall of the casing opposite the indentation side thereof, an electric 65 light arranged in the casing control means

for the light, and a strip of thin flexible material wound on the spools and extending between them across the sight opening.

2. In a device of the character described a casing having a sight opening, two spools 70 removably mounted at opposite ends of the casing, a strip of thin flexible material wound on the spools to extend across the sight opening, an electric bulb carried in a socket arranged in the casing, control 75 means for the electric bulb, said control means comprising a contact mounted on an arm to be insulated from the socket, the arm being adapted to normally hold the contact out of engagement with the bulb and be manually 80 actuated to move the contact into engagement with the bulb, and means in connection with the arm for actuating it from the exterior of the casing and holding it in its actuated position.

3. In a device of the character described, a casing comprising a base and a body hinged to the base, the body comprising ends, sides each having bores and one only having 90 indentations at the bores, and a sight opening, two rods carried in the bores to extend through the casing and so that each rod has only one end removable from the bore which carries it, two spools, one removably carried on each rod to have one end engage an indentation, means for preventing relative rotary movement between the spools and the rods, means for yieldingly holding the spools 95 against the indentations, said means comprising resilient members arranged on the rods 100 at the other ends of the spools, and contacting with the inner face of the casing, a strip of thin flexible material wound on the spools to extend between them, means for guiding the strip of material across the sight opening, a socket mounted in the casing, a bulb arranged in the socket, an arm mounted in the casing, a contact carried by the arm to be insulated from the socket, the arm being adapted to normally hold the contact out of 105 engagement with the bulb and adapted to be actuated to bring the contact into engagement with the bulb, and means in connection with the arm for actuating it from the exterior of the casing and releasably holding it 110 in its actuated condition.

4. In a device of the character described, a casing comprising a base, the body being formed with a sight opening, two spools, means for removably mounting the spools in 115 the casing, a strip of thin flexible material wound on the spools to extend between them and across the sight opening, a bracket secured to the rear end of the casing, a socket mounted on said bracket, a bulb in said 120 socket, and means in said bracket for the reception of a book.

5. In a device of the character described, a casing comprising a base and a body detachably hinged to the base, the body compris- 130

ing ends, sides each having bores and one only having indentations at the bores, and a sight opening, two rods carried in the bores to extend through the casing and so that each 5 rod has only one end removable from the bore which carries it, two spools, one removably carried on each rod to have one end engage an indentation, means for preventing relative rotary movement between the spools 10 and the rods, means for yieldingly holding the spools against the indentations, said means comprising resilient members arranged on the rods at the other ends of the spools, and contacting with the inner face of 15 the casing, a strip of thin flexible material wound on the spools to extend between them, means for guiding the strip of material across the sight opening, a bracket mounted on the base to form a carrier for a book, a 20 socket mounted on the bracket, a bulb arranged in the socket, an arm mounted in the casing, a contact carried by the arm to be insulated from the socket, the arm being adapted to normally hold the contact out of 25 engagement with the bulb and adapted to be actuated to bring the contact into engagement with the bulb, and means in connection with the arm for actuating it from the exterior of the casing and releasably holding it 30 in its actuated condition.

6. In a device of the class described, a casing comprising a base, a body hinged to the lower end thereof, said casing having sides one of which has indentations protruding 35 from its inner face, a transparent front, end openings in said sides and indentations, rods extending through said openings, spools journaled in said rods, recesses in said spools adjacent the side opposite the indentations, keys on the rods extending into said 40 recess for locking the rods to said spools, means on said rods contacting with the casing for yieldingly holding the spool in engagement with the indentation, and a strip

of flexible material wound in the spools and 45 extending between them across the transparent end.

7. In a device of the character described, a casing comprising a base, a body hinged to the lower end thereof, said base having sides, 50 one of which has indentations protruding from the inner face, ends, a sight opening, rods extending through said sides, spools journaled in said rods, a washer mounted on the rods adjacent the end opposite the indentations, and resilient means contacting with the washer and the inner face of the casing forcing the spools into engagement with the indentations, a strip of flexible material wound on the spools and extending between them across the sight opening. 55

8. In a device of the class described, a casing comprising a base, a body hinged to the lower end thereof, said base having sides one of which has indentations protruding from 60 its inner face, a transparent front end, openings in said sides and indentations, rods extending through said openings, spools journaled on said rods, resilient means on said rods between the spools and the inner face 65 of the casing for yieldingly holding the spools in engagement with said indentations, a strip of flexible material wound on the spools and extending between them across the transparent front end, a bracket secured 70 to the base member, a socket on said bracket, a bulb in said socket, and manually operating means extending through the base for forming an electric contact to light said 75 bulb. 80

In witness that we claim the foregoing we have hereunto subscribed our names this 22d day of March 1921.

EARL W. MASON.
CHESTER D. MILLER.
